DRUM FOR HOLDING FLEXIBLE TYPE
HOLDING CHASES

Frank H. Poeppelmeier, Dayton, Ohio, assignor,
by mesne assignments, to Set-O-Type Manufacturing Company, Cleveland, Ohio, a corporation of Delaware

Application December 17, 1931, Serial No. 581,659

12 Claims. (Cl. 101—415.1)

This invention relates to new and useful improvements in drums for holding flexible type-holding chases.

It is one of the principal objects of my invention 5 to provide a circular drum composed of sheet metal stampings assembled to form a light, rigid and economical form at low cost.

It is another object of my invention to provide on my improved circular form, simple means for 10 securely attaching flexible type-holding chases to its outer contour.

Other important and incidental objects of my invention will be set forth in the following specification and subjoined claims.

15 In the accompanying drawing illustrating my invention, Figure 1 is an end view of my new circular form. Figure 2 is a longitudinal section on the line 2—2 of Figure 1. Figure 3 is a cross-sectional view taken on the line 3—3 of Figure 2.

20 Figure 4 is an end view of one of the flexible type chases to be applied to my circular form. Figure 5 is a plan view of one end of one of the flexible type chases, showing the formed ends of the bands. And Figure 6 shows several of the chases 25 assembled on the bands.

Referring to the accompanying drawing for a detailed description of my invention therein illustrated, the numeral 1 designates a rectangular plate bent to circular form and having attached 30 to its inside face semi-circular reinforcing ribs 2. The ribs 2 are provided on their peripheries with laterally formed ears 3 to receive countersunk rivets 4 by which these ribs are secured to the circular plate 1, or they may be welded thereto.

35 Each of the ribs 2 is concave on its inner face, and at one side where it meets the plate 1, is provided with a lug 5. These lugs 5 are apertured to receive therethrough a hinge pin 6 whose outer ends, where they extend beyond the outside ribs 40 2, are peened for retention in place.

Above the hinge pins 6, and adjacent the inside face of the plate 1, each rib 2 is apertured to receive therein a rectangular clamp bar 7 whose lower face is provided with a longitudinal V-shaped groove 8. This bar 7, like the pin 6, has its ends peened to hold it in place.

45 Mounted on the hinge pin 6 adjacent each outer rib 2 are two clamp fingers 9—9 held in spaced relation by a spacer bar 10 riveted between its outer end adjacent the inner face of the plate 1.

50 Where the fingers 9 pass beyond the plate 1, its lower edge is provided with registering notches 11 to permit an upward travel of the fingers and to 55 retain them in the proper lateral position to re-

ceive the flexible bands to be hereinafter described.

Each of the fingers, between the spacer bar 10 and the hinge pin 6, is provided with a vertically extending stop lug 12 that engages the face of the 60 clamp bar 7 to prevent the outer ends of the fingers from dropping out of the notches 11 in the plate 1. Also beyond the pin 6, each finger 9 has an apertured ear 13 to receive one end of a tension spring 14 whose other end is secured to a 65 spring support pin 15 that, like the pin 6, extends through the ribs 2 and is riveted in place.

Each of the spacer bars 10 midway between the fingers 9—9, is threaded to receive a clamp screw 16 whose upper end is received by the groove 8 in 70 the bar 7 and has integral with its lower end a knurled head 17. These clamp screws securely lock the strap bands and assembled composition in place upon the drum.

75 My flexible type-holding chase that is applied to the periphery of my circular drum, comprises type channels 18 consisting of channel-shaped members 19 arranged back to back and spot welded together.

One end of each tube 18 is partially closed by 80 ears 20—20 punched from its top flanges and turned downwardly to retain the type within the channel.

Above the foot portions of the channel-shaped members 19 the vertical walls are provided with 85 slots through which flexible strap bands 22 pass. (See Figures 4, 5 and 6).

Each of the bands 22 is of sufficient length to extend around the face of the plate 1. At one end each band is provided with an elongated slot 90 23 to receive one of the fingers 9, and at the other end, it is provided with a hook-shaped terminal 24 to engage the edge of the plate 1. (See Figures 1, 4 and 5).

The type channels are free to be moved along 95 the bands 22 to permit the grouping or assembling of the composition at any desired points about the periphery of the drum; and then, with the terminal 24 engaging one edge of the plate, the fingers 9—9 are depressed until their outer ends enter the slots 23. Now, when the pressure is released, the springs 14—14 will force the fingers 9—9 outwardly to retain the bands in place until the thumb screw 16 is tightened against the V-groove 8 to securely lock the bands 100 and assembled composition in place.

When it is desired to remove the composition and bands, the thumb screw 16 is loosened and the fingers 9—9 depressed, permitting the slotted ends of the bands to be removed from the fin- 110

gers, after which the entire composition may be removed without destroying it.

Having described my invention, I claim:

1. A device of the type described, comprising a segment of a drum, arcuate ribs secured to the inner side of the segment, a hinge pin secured between the ribs adjacent one arcuate end thereof, fingers pivotally secured to said hinge pin and adapted to engage a flexible chase mounted on the segment, the adjacent edge of the segment being formed with notches to receive said fingers, tension springs secured to the inner ends of the fingers, and stop means for retaining the fingers within said notches. 80
2. A device of the type described, comprising a semi-circular plate, semi-circular ribs secured to the underside of the plate, one edge portion of the plate being formed with notches, a hinge pin secured between the ribs at one end thereof, fingers pivotally secured to said hinge pin and occupying said notches, tension springs anchored to the segment and connected to the inner ends of the fingers to force the outer ends in the engaging direction, a longitudinal bar carried by the segment on its inner side, clamp screws acting on the fingers and the bar to lock the fingers in engaged position. 85
3. The combination of a segment adapted to form a portion of a drum and having an internal arcuate web, a finger pivoted to the web adjacent one end, projecting beyond the outer edge of the segment and having a notch in the edge distant from the segment, a spring acting on the finger, tending to swing the notched edge away from the segment, and a set screw acting on the finger and adapted to positively push the notched edge away from the segment. 90
4. The combination of a segment adapted to form a portion of a printing drum, said segment having internal stiffening members, a rod carried by said members adjacent the edges of the segment, a pair of fingers on said rod, springs acting on the fingers to swing the outer edge away from the segment, a spacer bar connecting the fingers, a clamping bar carried by the segment, and a set screw extending through the spacer bar and acting on the clamping bar to lock the pair of fingers. 100
5. A device of the type described comprising a segment having a smooth exterior, internal webs, a rod carried by the webs, two pairs of pivoted fingers on the rod, said fingers projecting beyond the arcuate surface of the segment and adapted to engage openings in spaced straps of a chase on the segment, springs attached at one end to the fingers, and a rod carried by the segment to which the other ends of the springs are attached. 105
6. In a device of the character described, the combination of a segment of a drum on which a flexible chase is adapted to be mounted, a plurality of pivoted fingers carried by the segment and adapted to individually engage the chase, springs acting individually on the fingers and tending to swing them in the engaging direction, and means for positively forcing the fingers in the engaging direction. 110
7. In a device of the character described, the combination of a segment of a drum on which a flexible chase is adapted to be mounted, a plurality of pivoted fingers carried by the segment and adapted to individually engage the chase, 115
8. In a device of the character described, the combination of a segment of a drum on which a flexible chase is adapted to be mounted, a plurality of pivoted fingers carried by the segment and adapted to individually engage the chase, springs acting individually on the fingers and tending to swing them in the engaging direction, a cross member connecting adjacent pairs of fingers, and a set screw operating the cross member to cause said pair of fingers to be blocked against releasing movement. 120
9. In a device of the character described, the combination of a segment having a smooth exterior on which may be mounted a flexible chase, said segment having internal arcuate bracing ribs, a longitudinal rod carried by said ribs, a set of individually movable fingers mounted on the rod and projecting beyond the periphery of the segment and adapted to engage openings in the flexible chase mounted on the segment, springs attached to the fingers individually and tending to force each one in the direction away from the edge of the segment to tension the chase, members connecting the fingers in pairs, a continuous longitudinal clamping bar carried by the segment, and set screws one for each pair of fingers acting on the member connecting the pair and on the clamping bar to positively block the fingers against releasing movement. 125
10. In a device of the character described, the combination of a segment having a smooth exterior on which may be mounted a flexible chase, said segment having internal arcuate bracing ribs, a longitudinal rod carried by said ribs, a set of individually movable fingers mounted on the rod and projecting through arcuately extending notches in the segment and adapted to engage openings in the flexible chase mounted on the segment, springs attached to the fingers individually and tending to force each one in the direction away from the edge of the segment to tension the chase, members connecting the fingers in pairs, a continuous longitudinal clamping bar carried by the segment, and set screws one for each pair of fingers acting on the member connecting the pair and on the clamping bar to positively block the fingers against releasing movement, and means to limit the outward movement of the fingers under their spring action. 130
11. The combination of a segment adapted to carry a flexible printing chase, a pivoted finger carried by the segment adjacent one edge and adapted to engage the chase, a tongue on the finger and an abutment carried by the segment, adapted to be engaged by the tongue to limit the movement of the fingers. 135
12. In a segment adapted to carry a flexible type chase, fingers pivoted to the segment adjacent one edge, a cross bar connecting the adjacent fingers, a set screw mounted in the cross bar, a longitudinal bar carried by the segment against which the set screw bears to force the fingers away from the segment, and tongues on the fingers extending behind the cross bars to limit such movement of the fingers. 140

FRANK H. POEPPELMAYER.
